DISPENSING CARTON
Lafayette A. Robinson, New York, N.Y.
(302 Clinton Ave., Brooklyn, N.Y.)
Filed Dec. 6, 1963, Ser. No. 328,559
19 Claims. (Cl. 229—20)

The invention relates to dispensing cartons having a receptacle body portion which is slidable lengthwise and telescopically receivable within a tubular sleeve. The invention is also directed toward the forming of such dispensing cartons from single blanks.

Some dispensing cartons having the foregoing basic characteristics have been known in the prior art but the cartons of the present invention possess some inherent advantages over those of the prior art. The prior art cartons did not include full inner receptacles, a demi-top and locking detents for positively releasably retaining the lid closed over the tubular sleeve and the receptacle. Instead they generally employed inner receptacles lacking either a front or a back with the consequence that the structure was weakened. Many of the prior art devices, which were formed from single blanks, did not include lids of sufficiently strong structure to give full protection to the product contained in the carton or to produce a carton having a closure which might be operated easily while retaining good esthetic appeal.

Moreover, the prior art devices of the type similar to that of the instant invention did not contain means, integral with the carton, to insure a firm closure of the carton while at the same time offering a minimum resistance to the opening of the carton with one hand.

Accordingly, it is an important object of the invention to provide a dispensing carton which may easily be opened and closed with one hand.

It is a further object of the invention to provide such a carton which may be formed from a unitary blank.

It is a still further object of the invention to provide such a carton wherein the inner receptacle is completely enclosed.

It is a still further object of the invention to provide such a carton wherein the closure is made firm and secure by means of cooperating elements on the lid and the tubular sleeve or the receptacle.

It is a still further object of the invention to provide such a carton wherein the lid side walls and the tubular sleeve side walls are flush so as to form an uninterrupted smooth wall.

It is a still further object of the invention to provide a unitary blank from which such cartons may be formed.

These and other objects, features, advantages and uses will be apparent during the course of the following description when taken together with the accompanying drawings wherein:

FIGURE 1 is a top plan view of the blank for one form of carton of the invention;

FIGURE 2 is a top plan view of the carton formed from the blank of FIGURE 1;

FIGURE 3 is a front elevational view of the carton of FIGURE 2;

FIGURE 4 is a bottom plan view of the carton of FIGURE 2;

2

FIGURE 5 is a rear elevational view of the carton of FIGURE 2;

FIGURE 6 is a perspective view, viewed from the front, of the carton of FIGURE 2 in the closed position;

5 FIGURE 7 is a perspective view, viewed from the front, of the carton of FIGURE 2 in the open position;

FIGURE 8 is a perspective view, viewed from the rear, of the carton of FIGURE 2 in the open position;

FIGURE 9 is a vertical sectional view taken on the lines 9—9 of FIGURE 7, viewed in the direction of the arrows;

FIGURE 10 is a horizontal sectional view taken on the lines 10—10 of FIGURE 7, viewed in the direction of the arrows;

15 FIGURE 11 is a top plan view of the blank for another form of carton embodying the teachings of the invention;

FIGURE 12 is a top plan view of the carton formed from the blank of FIGURE 11;

20 FIGURE 13 is a front elevational view of the carton of FIGURE 12;

FIGURE 14 is a bottom plan view of the carton of FIGURE 12;

FIGURE 15 is a rear elevational view of the carton of FIGURE 12;

25 FIGURE 16 is a perspective view, viewed from the front, of the carton of FIGURE 12 in the closed position;

FIGURE 17 is a perspective view, viewed from the front, of the carton of FIGURE 12 in the open position;

FIGURE 18 is a vertical sectional view taken on the lines 18—18 of FIGURE 17, viewed in the direction of the arrows;

30 FIGURE 19 is a horizontal sectional view taken on the lines 19—19 of FIGURE 17, viewed in the direction of the arrows; and

35 FIGURE 20 is an enlarged sectional view taken on the lines 20—20 of FIGURE 16, viewed in the direction of the arrows, and showing the snap lock device used in cartons of the invention.

In the drawings, wherein, for the purpose of illustration, are shown two embodiments of the invention, the numeral 30 designates the unitary blank from which the embodiment of FIGURES 2 through 10 is formed. Blank 30 is a unitary blank comprising three panel elements: receptacle 32, lid 33 and tubular sleeve 34. In FIGURE 45 1, solid lines, which are interior of the outline of blank 30, are lines along which the adjacent elements have been separated by cutting or a similar operation. The dot and dash lines of FIGURE 1 designate the score lines between the panels or sections of panels along which folding or hinging occurs. The stippled areas indicate panels or sections of panels or flaps to the upper surface of which adhesive glue has been applied. Adhesive glue is also applied to the under surfaces of outer flap panel 58 and lid side walls 57 (FIGURE 1) and lid top wall 106 and lid side walls 110 (FIGURE 11).

The folding sequence for forming the dispensing carton of FIGURES 2 through 10 from the blank of FIGURE 1 is indicated by the numerals 74—1 through 74—15; 74—1 is the first fold and 74—15 is the last fold. The carton of FIGURES 2 through 10 is formed as follows: the blank 30 is cut and scored as shown in FIGURE 1; next, the adhesive glue is applied to the selected areas of the upper surface of blank 30 as indicated in FIGURE 1 and to the

under surfaces of outer flap panel 58 and lid side walls 57. Demitop 36 is folded up along score line 74-1 so as to be perpendicular to front wall 42. Top corner flaps 38, which were carried to the position perpendicular to front wall 42 when the demitop 36 was folded along score 74-1, are now folded along score lines 74-2. This action puts flaps 38 in positions in which they are each perpendicular to demitop 36 and front wall 42. Bottom corner flaps 50 are now folded up along score lines 74-3 so that they are perpendicular to inner side walls 40.

Inner side walls 40 are now folded up along score lines 74-4 so as to be perpendicular to front wall 42. This brings the sections of side walls 40, which are coated with adhesive, into contact with top corner flaps 38 and the elements are pushed together under pressure so as to be joined by the adhesive. The folding of inner side walls 40 also caused bottom corner flaps 50 to take positions perpendicular to both front wall 42 and side walls 40. Now the product is laid into the receptacle on the inner face of front wall 42.

Next, bottom wall 48 is folded up along score line 74-5 so that it is perpendicular to front wall 42 and inner side walls 40. This action causes the glued sections 49 of bottom wall 48 to come into contact with bottom corner flaps 50 which are pushed into pressure contact with areas 49 so that the elements are joined. Now, rear wall 46 is folded along score line 74-6 so that it overlays the product which has been placed on front wall 42. This action also carries glued side walls 44 into positions overlaying previously folded inner side walls 40. The folding along score line 74-6 also carries tubular sleeve blank 34 to a position to the left of the left edge of FIGURE 1 and parallel to the plane of front wall 42. Now, the glued side walls 44 are folded along score lines 74-7 to cause side walls 44 to overlay inner side walls 40. The adhesive carried on walls 44 causes the sets of panels to adhere to each other and adequate pressure is applied to join the walls 44 to the walls 40. This completes the formation of the inner receptacle of the carton.

To complete the formation of the carton, it is necessary to form the tubular sleeve around the filled receptacle and to form the lid so it closes over the receptacle. The lid side walls 54 are folded toward the completed receptacle along score lines 74-8. The balance of blank 30 (33 and 34) is folded upward along score line 74-9 so that it is perpendicular to top hinged flap 52. Next, the receptacle blank 32 is moved to the left along score line 74-10 so that the adhesive on the under side of outer flap panel 58 is pushed into contact with connecting panel 56. Pressure is applied to join the two panels. At this stage, back wall 60 overlays receptacle back wall 46.

Now, the panel 34 is folded along score line 74-11 so that it overlays the filled receptacle. Next, side wall 66 and the balance of blank 34 (side wall 64, front wall 62 and side wall 68) are folded along score lines 74-12. Then wall 62 is folded along score line 74-13 so that it is in front of front wall 42 of the receptacle. Now, wall 68 is folded along score line 74-14 so that it is brought into contact with the adhesive on wall 66 and the walls are put under pressure to join them together. As the final step in the formation of the carton, glued, lid side walls 57 are folded into contact with side walls 54 so that they are joined together by the adhesive on side walls 57. Sufficient pressure is applied to make the joining permanent. The top of the tubular sleeve is pushed down so that outer locking protuberances 70 mate with the inner openings 72 to hold the completed carton in the closed position. The package is opened by pushing upward on the underside of bottom wall 48 which causes the lid to move toward the rear along hinge 73. The lid moves away from the receptacle easily because back wall 60 is provided with score lines 75 which permit the upper portion 61 of rear wall 60 to flex and move outwardly away from the receptacle.

The completed carton, which is in the shape of a rec-

tangular parallelepiped, is used in the following manner: the outer wrapping, if any, is removed and the receptacle is moved upward inside the tubular sleeve by pushing upward on bottom wall 48. This raises the lid and permits the user to remove some of the product from the receptacle. To reclose the carton, the user pushes down on demitop 36 until the receptacle is completely within the tubular sleeve. Then, the lid is pushed over the carton so that the mating protuberances and openings lock the lid in place.

It can easily be seen that the carton of FIGURES 2 through 10, which is formed from the blank of FIGURE 1, comprises a completely enclosed inner receptacle and an outer tubular sleeve. The receptacle structure is strong and will withstand all the normal digital pressure which is required to make the carton function in its intended manner. Since the receptacle is a closed unit, it may be used to hold all types of product such as pellets, cigarettes and the like. The demitop permits the user to close the carton easily without having to twist the wrist in order to exert the necessary pressure on the lid.

In FIGURE 11 there is illustrated the unitary blank 80 from which a further embodiment of the invention may be formed. Blank 80 comprises three panels: receptacle panel 82; lid panel 83 and tubular sleeve panel 84. The blank 80 will, when formed and folded in accordance with the description and drawings, produce a dispensing carton having smooth, flush side walls. In this embodiment of the invention the side walls of the lid and of the tubular sleeve form a continuous smooth wall when the lid is closed over the tubular sleeve and receptacle. The stippled areas of the blank indicate the upper surface areas to which adhesive is applied. The adhesive is also applied to the under surfaces of lid top wall 106 and lid side walls 110. The folding sequence is indicated by the numerals 124-1 through 124-15 wherein 124-1 is the first fold and 124-15 is the last fold.

The dispensing carton formed from the blank of FIGURE 11 is illustrated in FIGURES 12 through 20. In its completed, closed form it takes the shape of a rectangular parallelepiped and is formed as follows: the blank is cut and scored as shown in FIGURE 11; the adhesive glue is next applied to the selected areas of blank 80 as shown in the figure. The folding of the blank, the placement of the product on the front wall 92 of the receptacle and the gluing together of the appropriate elements are carried out in the same manner as has been previously described in connection with the formation of the carton of FIGURES 2 through 10. The folding on line 124-1 corresponds to the folding on line 74-1 and the folding on lines 124-2 through 124-15 corresponds to that on lines 74-2 through 74-15.

After the carton has been filled and formed, it takes the shape, when closed, of a rectangular parallelepiped as shown in FIGURES 12 through 19. In FIGURE 16 it can be seen that the outer side wall 110 of the lid is flush with outer side wall 118 of the tubular sleeve. This construction permits the package to be wrapped in an outer cellophane wrap without any danger of tearing by the edges of the overlapping lid. One side wall 90 of the receptacle carries opening 93 which cooperates with one of the locking protuberances 112 which is formed on lid inner side wall 108.

The other locking opening 113 is formed in inner side wall 120 of the tubular sleeve. The top corner flaps 88 of the receptacle are held in place by glued areas 91 of inner side walls 90 and serve to hold demitop 86 in position. Outer side walls 94 are glued to inner side walls 90 and serve to hold the receptacle together. Bottom corner flaps 96 are affixed to glued areas 99 on bottom wall 98 and serve to hold the bottom of the receptacle in position. Rear wall 100 of the receptacle is hinged to the hinged flap 102 of the lid along the scored hinge line 123. Top wall 106 of the lid is glued to connecting flap 104 and its side walls 110 are affixed to side walls 108

to form the lid of the carton. Rear wall 114 of the tubular sleeve is scored at 125 so as to permit the upper portion 115 of wall 114 to flex and move outwardly away from the receptacle when the receptacle is moved upward within the tubular sleeve. Front wall 116 and outer side walls 118 and 119 complete the formation of the tubular sleeve. Outer wall 119 is cut away as shown in FIGURE 11 to permit locking opening 113 on inner side wall 120 to mate with a locking protuberance 112.

The carton of FIGURES 12 through 20 may be opened and closed with one hand in the same manner as that used for opening and closing the carton of FIGURES 2 through 10.

It is also within the contemplation of the invention to cut away inner side wall 120 in the same manner as wall 119 is shaped and to place the locking opening on the other wall 90 of the receptacle. Such a carton would have one locking opening 93 on each inner side wall 90 of the receptacle. To assist in keeping the carton in its closed position and still permit the lid to be easily released under digital pressure on the bottom wall of the receptacle, the locking openings are provided with upturned raised edges 122 as shown in FIGURE 20. The figure shows the placement of the opening and the protuberance with respect to the side walls and each other when the carton is in its closed position.

It will be apparent that the cartons of the invention are not to be limited to the embodiments set forth in the drawings and description, that the cartons may be formed of any suitable material such as paper, cardboard, metal, plastic or combinations of them, and that variations may be made in form and construction without departing from the spirit and scope of the invention as defined in the appended claims.

Having thus described my invention, I claim:

1. A dispensing carton comprising:

an inner receptacle having front, rear, side and bottom walls;
an outer tubular sleeve having front, rear and side walls corresponding to the receptacle front, rear and side walls, respectively, the sleeve telescopically engaging the receptacle for lengthwise relative sliding motion; and
a lid for providing a cover over the sleeve and the receptacle, the lid having a top wall with rear and side walls depending therefrom at intersections therewith and wall edges opposite said intersections; the lid being hinged to the rear wall of the receptacle along a line adjacent the edge of the lid rear wall opposite the intersection of the lid rear wall and the top wall, and being hinged to the sleeve rear wall along a line adjacent the intersection; a portion of the sleeve rear wall being capable of movement outwardly away from the receptacle, said portion having a length greater than the distance between the lines at which the lid is hinged such that upon movement of the receptacle lengthwise out of the sleeve, said portion is moved outwardly and the lid is hinged open, and upon retraction of the receptacle lengthwise into the sleeve said portion is moved inwardly toward the receptacle and the lid is hinged closed over the sleeve and the receptacle with at least one of the lid side walls overlapping with one of the sleeve side walls.

2. A dispensing carton as described in claim 1 wherein first means are provided in at least one of the sleeve side walls for cooperatively engaging with second means provided in the overlapping lid side wall to positively releasably retain the lid closed over the sleeve and the receptacle when the receptacle is retracted within the sleeve.

3. A dispensing carton capable of being fabricated of a single blank suitably cut and scored comprising:

a receptacle provided with rectangular planar front, rear, side and bottom integral walls;
a tubular sleeve provided with rectangular planar front, rear and side walls corresponding to the receptacle front, rear and side walls, respectively, the receptacle being integral with the sleeve and being telescopically received within the sleeve for lengthwise relative sliding motion, the sleeve side walls having outer surfaces; and

rear and side walls corresponding to the receptacle front, rear and side walls, respectively, the receptacle being integral with the sleeve and being telescopically received within the sleeve for lengthwise relative sliding motion; and

- a lid providing a cover over both the receptacle and the sleeve and having a rectangular top wall with planar rear and side walls depending therefrom at intersections therewith, and wall edges opposite the intersections, the rear wall opposite edge being integral with the receptacle rear wall and the top wall being integral with the sleeve rear wall;
the lid being hingedly connected to the rear wall of the receptacle at the edge of the lid rear wall opposite the intersection of the lid rear wall and the top wall and hingedly connected to the rear wall of the sleeve at the intersection;
a portion of the sleeve rear wall being capable of movement outwardly out of the plane of the remainder of the rear wall away from the receptacle, the portion extending lengthwise from the intersection of the lid top and rear walls to a position along the sleeve rear wall lying further from the intersection than the distance between the intersection and the lid rear wall opposite edge such that upon movement of the receptacle lengthwise out of the sleeve, the portion is moved outwardly and the lid is hinged open, and upon retraction of the receptacle lengthwise into the sleeve the portion is moved inwardly toward the plane of the lid rear wall and the lid is hinged closed with at least one of the lid side walls overlapping with one of the sleeve side walls.

4. A dispensing carton as described in claim 3 wherein first means are provided in at least one of the sleeve side walls for cooperatively engaging with second means provided in the overlapping lid side wall to positively releasably retain the lid closed over the sleeve and the receptacle when the receptacle is retracted within the sleeve.

5. A dispensing carton as described in claim 4 wherein the first means comprises an outwardly projecting protuberance and the second means receives the protuberance in locking engagement.

6. A dispensing carton as described in claim 5 wherein the second means comprises an opening with an inwardly projecting lip about the periphery of said opening for releasably securing said protuberance within said opening.

7. A dispensing carton capable of being fabricated of a single blank suitably cut and scored comprising:

a receptacle provided with rectangular planar front, rear, side and bottom integral walls;
a tubular sleeve provided with rectangular planar front, rear and side walls corresponding to the receptacle front, rear and side walls, respectively, the receptacle being integral with the sleeve and being telescopically received within the sleeve for lengthwise relative sliding motion, the sleeve side walls having outer surfaces; and

a lid providing a cover over both the receptacle and the sleeve and having a rectangular top wall with planar rear and side walls depending therefrom at intersections therewith, and wall edges opposite the intersections, the rear wall opposite edge being integral with the receptacle rear wall and the top wall being integral with the sleeve rear wall, the lid side walls having outer surfaces;

the lid being hingedly connected to the rear wall of the receptacle at the edge of the lid rear wall opposite the intersection of the lid rear wall and the top wall and hingedly connected to the rear wall of the sleeve at the intersection;

a portion of the sleeve rear wall being capable of movement outwardly out of the plane of the remainder of the rear wall away from the receptacle,

the portion extending lengthwise from the intersection of the lid top and rear walls to a position along the sleeve rear wall lying further from the intersection than the distance between the intersection and the lid rear wall opposite edge such that upon movement 5 of the receptacle lengthwise out of the sleeve, the portion is moved outwardly and the lid is hinged open, and upon retraction of the receptacle lengthwise into the sleeve the portion is moved inwardly toward the plane of the lid rear wall and the lid is hinged closed with the outer surfaces of corresponding sleeve and lid side walls lying in the same plane and being contiguous so that said carton, when closed, presents a rectangular parallelepiped, the side wall surfaces of which parallelepiped are comprised of said contiguous sleeve and lid side wall outer surfaces.

8. A dispensing carton as described in claim 7 wherein said lid is hinged closed with at least one of the lid side walls overlapping with at least a portion of a corresponding sleeve side wall.

9. A dispensing carton as described in claim 8 wherein first means are provided in the overlapping lid side wall for cooperatively engaging with second means provided in the corresponding sleeve side wall to positively releasably retain the lid closed over the sleeve and the receptacle when the receptacle is retracted within the sleeve.

10. A dispensing carton as described in claim 9 wherein the first means comprises an inwardly projecting protuberance and the second means receives the protuberance in locking engagement.

11. A dispensing carton as described in claim 10 wherein the second means comprises an opening with an outwardly projecting lip about the periphery of the opening for releasably securing the protuberance within the opening.

12. A dispensing carton as described in claim 7 wherein the lid is hinged closed with at least one of the lid side walls overlapping with at least a portion of a corresponding receptacle side wall.

13. A dispensing carton of claim 12 wherein first means are provided in the overlapping lid side walls for cooperatively engaging with second means provided in the corresponding receptacle side wall to positively releasably retain the lid closed over the receptacle and the sleeve when the receptacle is retracted within the sleeve.

14. A dispensing carton as described in claim 13 wherein the first means comprises an inwardly projecting protuberance and the second means receives the protuberance in locking engagement.

15. A dispensing carton as described in claim 14 wherein the second means comprises an opening with an outwardly projecting lip about the periphery of the opening for releasably securing the protuberance within the opening.

16. A unitary blank capable of being folded along score lines into a dispensing carton having a receptacle, a tubular sleeve telescopically engaging the receptacle for lengthwise relative sliding motion and a lid hinged to the receptacle and to the sleeve for providing a cover over the receptacle and the sleeve, the cover being operated between open and closed positions by the relative sliding motion, said blank comprising:

a first panel having first parallel score lines defining receptacle front, rear and side walls and second score lines perpendicular to the first score lines defining a bottom wall intermediate the front and rear walls;

a second panel contiguous with the first panel and having first parallel score lines defining lid top wall portions and second score lines perpendicular to the first score lines defining first and second flap portions for forming lid side walls, the first panel having slits along a part of the first parallel score lines to define a portion for forming a lid rear wall of a given length;

a third panel contiguous with the second panel and

having parallel score lines defining sleeve front, rear and side walls corresponding to the front, rear and side walls of the receptacle, and slits along a part of the length of the score lines defining the sleeve rear wall to define a portion of said sleeve rear wall having a length greater than the length of the lid rear wall forming portion;

at least one of the flap portions being provided with an opening therein and the corresponding sleeve side wall being provided with a protuberance for engaging said opening when the lid is in said closed position to releasably retain the lid in said position.

17. A unitary blank capable of being folded along score lines into a dispensing carton having a receptacle, a tubular sleeve telescopically engaging the receptacle for lengthwise relative sliding motion and a lid hinged to the receptacle and to the sleeve for providing a cover over the receptacle and the sleeve, the cover being operated between open and closed positions by the relative sliding motion, said blank comprising:

a first panel having first parallel score lines defining receptacle front, rear and side walls and second score lines perpendicular to the first score lines defining a bottom wall intermediate the front and rear walls;

a second panel contiguous with the first panel and having first parallel score lines defining lid top wall portions and second score lines perpendicular to the first score lines defining first and second flap portions for forming lid side walls, the first panel having slits along a part of the first parallel score lines to define a portion for forming a lid rear wall of a given length;

a third panel contiguous with the second panel and having parallel score lines defining sleeve front, rear and side walls corresponding to the front, rear and side walls of the receptacle, and slits along a part of the length of the score lines defining the sleeve rear wall to define a portion of said sleeve rear wall having a length greater than the length of the lid rear wall forming portion;

at least one of the flap portions being provided with a protuberance and the corresponding sleeve side wall being provided with an opening therein for receiving the protuberance when the lid is in said closed position to releasably retain the lid in said position.

18. A unitary blank capable of being folded along score lines into a dispensing carton having a receptacle, a tubular sleeve telescopically engaging the receptacle for lengthwise relative sliding motion and a lid hinged to the receptacle and to the sleeve for providing a cover over the receptacle and the sleeve, the cover being operated between open and closed positions by the relative sliding motion, said blank comprising:

a first panel having first parallel score lines defining receptacle front, rear and side walls and second score lines perpendicular to the first score lines defining a bottom wall intermediate the front and rear walls;

a second panel contiguous with the first panel and having first parallel score lines defining lid top wall portions and second score lines perpendicular to the first score lines defining first and second flap portions for forming lid side walls, the first panel having slits along a part of the first parallel score lines to define a portion for forming a lid rear wall of a given length;

a third panel contiguous with the second panel and having parallel score lines defining sleeve front, rear and side walls corresponding to the front, rear and side walls of the receptacle, and slits along a part of the length of the score lines defining the sleeve rear wall to define a portion of said sleeve rear wall having a length greater than the length of the lid rear wall forming portion;

at least one of the flap portions being provided with first means and the corresponding receptacle side wall being provided with second means for cooperatively engaging the first means when the lid is in said closed position to releasably retain the lid in said position.

19. A unitary blank as described in claim 18 wherein the first means comprises a protuberance and the second means comprises an opening.
